ATTORNEY

UNITED STATES PATENT OFFICE.

PAULO SCHELIGA, OF WASHINGTON, DISTRICT OF COLUMBIA.

EDUCATIONAL DEVICE.

Application filed September 21, 1923. Serial No. 664,104.

To all whom it may concern:

Be it known that I, PAULO SCHELIGA, citizen of Brazil, residing at Washington, in the District of Columbia, have invented 5 new and useful Improvements in Educational Devices, of which the following is a specification.

This invention relates to improvements in educational devices and has for an object the provision of an amusing and instructive device whereby the alphabet, spelling, reading and number work may be taught in a manner to entertain and hold the attention of the pupil.

15 Another object of the invention is the provision of a device of this character which is neat and attractive in appearance and which may also be utilized as a game.

With the above and other objects in view, 20 the invention further includes the following novel features and details of construction, to be hereinafter more fully described, illustrated in the accompanying drawings and pointed out in the appended claim.

25 In the drawings:—

Figure 1 is an elevation.

Figure 2 is a vertical section with the parts in normal position.

Figure 3 is a similar view showing the 30 container elevated.

Figure 4 is a top plan view with the cover of the container removed.

Referring to the drawings in detail where- 35 in like characters of reference denote cor- responding parts, the device which may be made of any suitable material includes a base 10. Rising from this base is a stand- ard 11, the latter having a reduced threaded portion 12 which engages a threaded open- 40 ing 13 provided in the base.

Surrounding and movable longitudinally upon the standard 11 is a sleeve 14 which carries at its upper end a container 15, the latter being provided with a removable top 45 16. This container is provided with an opening 17 while the base of the container is provided with an opening 18. Extending from the last mentioned opening and into the opening 17 is a reduced extension 50 19 of the standard 11. The extremity of this extension is provided with a seat 20 which, when the parts are in the position shown in Figures 1 and 2 of the drawings provides a pocket or bottom for the flared 55 mouth 21 which surrounds the opening 17.

The cover 16 is also provided with an opening 22.

The bottom of the container 15 is pro- 60 vided with a spiral groove 23 which com- municates at its lowermost point with the opening 18, so that when the receptacle is elevated to the position shown in Figure 2, the seat or pocket 20 will be slightly lower than the lowermost portion of the spiral groove 23.

The container is designed to hold a num- 65 ber of balls 24 and the latter is provided with letters or numbers, the purpose being to deliver these balls singly through the flared mouth 21 of the opening 17. This is effected by raising the container to the 70 position shown in Figure 2 whereupon the ball 24 which occupies the lowermost position in the groove 23 will roll upon the seat 20 and when the container is lowered 75 the ball so seated will operate within the flared mouth 21, as shown in Figure 3 of the drawings. Downward movement of the container is limited by the engagement of the lower end of the sleeve with the base 80 10, while upward movement is limited by engagement of a flange 25 at the lower end of the sleeve with a flange 26 which surrounds the standard 11.

As the balls are removed from the con- 85 tainer they may be placed within pockets or depressions 27 provided in the base 10 and may be so arranged as to provide a particular combination of numbers or to spell a word, depending upon the charac- 90 ters upon the balls. The balls are replaced within the container through the opening 22.

As stated, the balls may be provided with either numbers or letters and in the former 95 case a game may be played, each player operating the device in turn until the number of balls agreed upon have been removed from the container. The total of the numbers upon the balls of each player is added 100 and the highest total wins.

When the balls bearing the letters are used, they are removed as above mentioned until each player has received an agreed upon number of balls. They are then ar- 105 ranged within the pockets 27 and the player supplying the greatest number of words with the letters contained upon his own balls wins the game.

From the foregoing it will be apparent 110

that the invention provides a device which is both educational and entertaining, the games played by the numbered balls teaching addition, while the games played with the lettered balls teach spelling and reading in an amusing and entertaining way.

The invention is susceptible of various changes in its form, proportions and minor details of construction and the right is herein reserved to make such changes as properly fall within the scope of the appended claim.

Having described the invention what is claimed is:-

15. A device of the class described embody-

ing a base, a standard rising from the base, a container having an opening therein, means connecting the standard and container whereby the latter may be supported for vertical movement, a seat at the upper 20 end of the standard, a plurality of movable elements within the container and a spiral raceway provided in the bottom of the container, whereby, when the container is moved vertically the movable elements will 25 be deposited singly upon the seat for passage through the opening of the container.

In testimony whereof I affix my signature.

PAULO SCHELIGA.
